DESIGN FOR A COMBINED BOTTLE AND
STAND THEREFOR

Jacques Heim, Paris, France

Application February 26, 1947, Serial No. 137,187

Term of patent 3½ years

(Cl. D58—8)

To all whom it may concern:

Be it known that I, Jacques Heim, a citizen of France, residing in Paris, France, have invented a new, original, and ornamental Design for a Combined Bottle and Stand Therefor, of which the following is a specification, reference being had to the accompanying drawing, forming part thereof, wherein,

Figure 1 is a perspective view of a combined bottle and stand therefor showing my new design.

Figure 2 is a side elevational view thereof.

I claim:

The ornamental design for a combined bottle and stand therefor, substantially as shown.

JACQUES HEIM.
